Frank C. Fischer
ATTORNEY

UNITED STATES PATENT OFFICE.

HERMAN RINGEL, OF NEWARK, NEW JERSEY, ASSIGNOR TO CONVERTERS PAPER COMPANY, OF NEWARK, NEW JERSEY, A CORPORATION OF NEW JERSEY.

CLOTHING RECEPTACLE.

Application filed January 26, 1925. Serial No. 4,876.

This invention relates to receptacles for containing clothing and other like articles during periods of dis-use, having as one of its objects to provide a strong container, 5 light in weight and easy to pack or unpack, one of its lateral edges being open its entire length when it is desired to obtain access to the interior.

Another purpose is to produce a container 10 in which provision is made for properly suspending articles of wearing apparel extended at full length to avoid folds, creases and wrinkles, so that the articles may be instantly available.

15 A further aim is in the provision of means for enseaming the edges surrounding the opening, almost or quite hermetically, preventing the entrance of dust, insects and like undesirable and destructive pests, as well as 20 light rays which might cause the garments to fade and thus become damaged.

These and analogous aims and objects are accomplished by the novel construction and combination of parts hereinafter described 25 and shown in the accompanying drawing, forming part hereof and in which:—

Figure 1 is a side elevational view of an embodiment of the invention as extended at 30 length and shown in a closed position.

35 Figure 2 is a fragmentary sectional view, drawn to an enlarged scale, the section being taken longitudinally through the upper portion, substantially on line 2—2 of Figure 3.

Figure 3 is a transverse sectional view of 40 the same, looking on line 3—3 of Figure 2.

Figure 4 is a further enlarged fragmentary perspective view, showing the latch securing means as applied in an operative position.

45 In common with other bags or receptacles of like nature the body 10 is an oblong rectangle in shape, made in any preferred color of strong dense paper or fiber folded at one of its longitudinal edges 11 and seamed at the top 12 and bottom 13, these seams being secured permanently by cement or like suitable strong adhesive.

50 The longitudinal edge of the front element 14 is relatively shorter than that of the rear element 15, between which is an opening extending the full length of the receptacle and through this opening access is had to the interior in entering and removing garments or other articles.

The rear element 15 has its extra width 55 curved as at 16 to produce a flap 17 folded tight upon itself presenting a parallel rounded edge 18, the inner member 19 being juxtaposed on the adjacent outer surface of the element 14, as can best be seen in Figure 60 4, affording a tight closure.

In order to maintain the seam thus formed closed to prevent the entrance of insects, dust or even air, a plurality of latches, generally designated by the numeral 20, are 65 used, the same consisting of a flat metallic strip shaped to present a lever 21 pivotally engaged on the outer surface of the rear element 15, by a rivet 22, the free end of the lever being curved outwardly at a right angle 70 and bent re-entrantly to provide a loop 23, adapted to encompass the outer curved edge 16, from which extends an arm 24, resting snugly over the surface of the flap 17, and terminating in an indent snap hook 25 engageable with the rounded edge 18, holding the folded seam in such manner as to tightly 75 embrace the parts and prevent separation or unfolding until the latches are manually released.

80 As the material is relatively stiff and creased at the folding lines, the latches merely act as retainers, confining the folds in proper position, and obviously as many of the latches may be used as is deemed desirable, these latches being readily released by raising the hook 25 and swinging the arm and lever outwardly upon the pivot 22.

85 At the top of the receptacle, inside and at about the center, is a re-enforcement composed of a single rectangular sheet of material similar to the receptacle walls and bent to produce two equal flaps 26 held to the walls by an adhesive as best shown in Figures 2 and 3.

90 A metal plate is sheared and bent to produce two substantially semi-circular portions 27 disposed inside the flaps 26 and an outer metal plate having like elements 28 is disposed over the structure, these plates being held together by prongs 29 formed integral with the inner plate 27, passed through openings 30 in the outer plate and bent tightly thereover.

95 Similar prongs 31 are formed in a like manner at the top, where narrow flat surfaces are presented by all the several members, thus binding the structure firmly in

cluding both plates, the re-enforcement and side walls of the receptacle.

An open hook 32 used to suspend the receptacle is formed with a stem 33 on which 5 is rigidly secured a washer 34, said washer 34 being revolvably located in the circular raised portion 37 of the outer metal plate having semi-circular portions 28, and disposed between the receptacle material and 10 outer plate.

The upper portion of the triangular metal loop 36 has rigidly secured thereto a washer 35, said washer 35 being revolvably located 15 in the circular depressed portion 38 of the inner metal plate having semi-circular portions 27, and disposed between the material of the re-enforcing flaps 26 and inner plate.

The hook 32 can be rotated in the circular raised portion 37 of the outer metal plate 20 and the triangular loop 36 can likewise be rotated in the circular depressed portion 38 of the inner metal plate in order that the ends of said loop 36 may be disposed transversely, pressing against the inner sides of 25 the interior elements 27 and re-enforcement, these members preventing puncturing or tearing of the receptacle walls and assisting in spreading them when entering or removing articles.

30 Although I have described my improvements with considerable detail and with respect to certain particular forms of my invention, I do not desire to be limited to such details since many changes and modifications 35 may well be made without departing from the spirit and scope of my invention in its broadest aspect.

Having thus described my invention, what

I claim as new and desire to secure by Letters Patent, is:—

1. In a garment receptacle having an upper edge, metallic re-enforcing plates disposed respectively at the interior and exterior of the receptacle at its upper edge, means integral with said plates for rigidly securing the plates to the receptacle walls and to each other, an open hook revolvably secured to the exterior re-enforcing plate and a loop revolvably secured to the interior re-enforcing plate and extending into the receptacle.

2. In a garment receptacle having an upper edge, metallic re-enforcing plates disposed respectively at the interior and exterior of the receptacle at its upper edge, re-enforcing flaps interjacent the inner plate and receptacle walls and secured to the walls of the receptacle, means integral with said plates for rigidly securing the plates to the receptacle walls, re-enforcing flaps and to each other, an open hook extending outwardly from the receptacle and revolvably secured to the exterior re-enforcing plate and a loop revolvably secured to the interior re-enforcing plate and extending into the receptacle.

3. In a garment receptacle having an upper edge, a support hook revolvably secured to said upper edge and revolvably garment supporting means carried by the top edge of the bag and located within the bag adapted when turned to separate the walls of the bag.

This specification signed and witnessed this 21st day of January, 1925.

HERMAN RINGEL.
